UNITED STATES PATENT OFFICE.

JOHN GRAMELSPACHER, OF JASPER, INDIANA.

DESIGN FOR A DESK.

SPECIFICATION forming part of Design No. 26,811, dated March 23, 1897.

Application filed February 4, 1897. Serial No. 622,055. Term of patent 7 years.

To all whom it may concern:

Be it known that I, JOHN GRAMELSPACHER, a citizen of the United States, residing at Jasper, in the county of Dubois and State of Indiana, have invented a new and original Design for a Desk, (Case A,) of which the following is a specification.

This invention relates to a new and original design for a desk; and it has for its object to provide a design of this character that shall be both useful and ornamental.

The leading feature of the design resides in a desk having a flat rectangular table supporting a cabinet-top provided with a curtain-covered open front portion and an upright back portion formed with a plurality of pigeonholes rectangular in form and some of which holes are arranged in vertical columns extending downward to the upper surface of the table and inclosing below the upper tier of holes a squared open space, a horizontal drawer-casing surmounting the table at one end portion thereof in front of the upright back portion of the cabinet-top, said casing having a flat table-top and receiving a drawer formed with an inclined front wall disposed adjacent to the front edge of the table, and a squared door fitted within the upright back portion of the cabinet-top at one end thereof directly at the rear and above the plane of said horizontal drawer-casing, said door having in its front face a square glass panel.

A minor feature of the design resides in combining with the features above enumerated angular drawers filling the upper corners of the squared open space of the upright back portion; a pendent drawer-holding pedestal arranged beneath the same end of the table as the horizontal drawer-casing surmounting the same, and ornamental molding-pieces fitted to the front corners of said drawer-casing and pedestal, said molding-pieces having a post-like appearance.

The drawing is a perspective view of a desk embodying the herein-described design.

Referring to the accompanying drawing, the numeral 1 designates a flat rectangular table

supporting a cabinet-top having opposite quadrantal upright end pieces 2, a curtain-covered open front portion, and an upright back portion. The upright back portion of the cabinet-top is formed with a plurality of pigeonholes 3, rectangular in form, and some of which holes are arranged in opposite vertical columns extending downward to the upper surface of the table 1 and inclosing below the upper tier of holes a squared open space 4. At the upper corners of the space 4 are arranged angular drawers 5 of a somewhat triangular form, and at the back of the space 4, parallel with the table 1, is arranged a transverse strip 6.

A horizontal drawer-casing 7 is arranged at one end portion of the table 1, in front of the upright back portion of the cabinet-top, and said casing 7 is provided with a flat table-top and receives a drawer 8, having an inclined front wall disposed adjacent to the front edge of the table. At the rear portion of the casing 7 and above the plane thereof is arranged a squared door 9, fitted within the upright back portion of the cabinet-top and having in its front face a square glass panel 10. Directly below that end of the table 1 supporting the casing 7 is arranged a pendent drawer-pedestal 11, holding a plurality of drawers, the lower one of which is of a greater size than those thereabove, and ornamental molding-pieces 12 are fitted to the front corners of the pedestal 11, the casing 7, and also to the front edge of the leg portion 13 of the desk, opposite the pedestal 12. The molding-pieces 12 are somewhat cylindrical in general form, so as to have a post-like appearance.

What I claim is—

The design for a desk herein shown and described.

In testimony that I claim the foregoing as my own I have hereto affixed my signature in the presence of two witnesses.

JOHN GRAMELSPACHER.
